(57) CLAIM

The ornamental design for the mom and son picture frame, as shown and described.

DESCRIPTION

FIG. 1 is a front elevational view of a mom and son picture frame of my new design;

FIG. 2 is a left side view thereof;

FIG. 3 is a right side view thereof;

FIG. 4 is a top plan view thereof;

FIG. 5 is a bottom view thereof; and,

FIG. 6 is a back elevational view thereof.

The shade lines in the Figures show contour and not surface ornamentation.

The broken lines in FIG. 6 show picture hanger and stand elements and form no part of the claimed design.
